John H. Rathbone of Albany, N.Y.
Letters Patent No. 1791, dated June 23, 1863.

The schedule referred to in these Letters Patent and making part of the same

I do know and I, John H. Rathbone of the City of Albany, State of New York, have produced and arranged a design for the plates of a Cooking Stove; and I hereby declare the drawings (photographs) forming part of this specification to be a full and complete delineation of the said plates, with their ornamental parts, the oven door and side panels not represented being symmetrically similar to those shown.

What I claim as my production and desire to secure by Letters Patent is the combination and arrangement of figures and forms above described, represented in the drawings.
